UNITED STATES PATENT OFFICE

FRANK ARATA AND JOT E. STILES, OF SACRAMENTO, CALIFORNIA

MERCHANDISE GUARD

Application filed December 19, 1929. Serial No. 415,324.

This invention relates to new and useful improvements in merchandise guards.

The primary object of the invention is to provide a guard of the character specified, especially adapted for use in wholesale houses and ware houses to protect the lower cases of piled merchandise at the corners from damage, as a result of being bumped by trucks running through the aisles in the ware houses in which such merchandise is stored.

A further object of the invention is to provide a merchandise guard which may be easily and readily manufactured at a relatively small cost from gauge iron or steel or other suitable material.

A still further object of my invention is to provide a merchandise guard which cannot be bumped out of place by a truck.

With the foregoing and other objects in view that will appear as the nature of the invention is better understood, the same consists in the novel features of construction, combination and arrangement of parts illustrated in the accompanying drawing and more particularly pointed out in the appended claim.

In the accompanying drawing, which is for illustrative purposes only and is therefore not drawn to scale:

Figure 1 is an enlarged inside perspective view of the merchandise guard per se.

Figure 2 is a side elevation, illustrating the application of the invention.

Figure 3 is an enlarged detail fragmentary view, showing one of the inwardly projecting retaining teeth or barbs and Figure 4 is a cross section, taken on line 4—4 of Figure 3.

Referring to the drawing for a more particular description of my invention and in which drawing like parts are designated by like reference characters throughout the several views, the device is preferably constructed from a single blank or piece of gauge iron, steel or other suitable metal and com-

prises the two corresponding upright right-angularly disposed straight flat side members 1 and 2, the straight flat horizontal transverse bottom member 3, which extends inwardly at right angles from the lower end of the side member 2 somewhat beyond the outer edge 4 of side member 1 and the vertical elongated transverse tongue 5 which is formed by a continuation of the bottom member 3. The tongue 5 fits against the inner face and lower end of the side member 1 and these parts are fastened together by rivets 6 or other equivalent means. The tongue 5 corresponds in length to the bottom member 3 and accordingly extends a corresponding distance beyond the outer edge 4 of the side member 1.

The metal guards are made in pairs and when applied the right-angularly disposed side members 1 and 2 fit over and embrace the outer exposed corners of the lower cases A of the piled merchandise and protect the same against damage as a result of being bumped by trucks running through the aisles in the ware-houses in which such merchandise is stored. The transverse bottom member 3 fits under the bottom of the corresponding case of piled merchandise and the tongue 5 against the adjacent side or end of the case.

In the event the guard should be bumped out of place by a truck, the whole stack of merchandise must be taken down and re-piled in order to replace the guard. Hence, in order to overcome or eliminate this objection, the side walls 1 and 2 as well as the bottom wall 3 of the guard is formed with a plurality of inwardly projecting hook-like teeth or barbs 7 which are punched out of the metal by a special punch (not shown). The tongue 5 may also be provided with one or more teeth or barbs 7.

From the foregoing description taken in connection with the drawing, it is thought that the construction, operation and advantages of the invention will be readily under-

stood without requiring a more extended explanation.

Various changes in the form, proportions and minor details of construction may be resorted to without departing from the principle or sacrificing any of the advantages of the invention as defined in the appended claims.

Having described the invention, what is claimed as new and desired to secure by Letters Patent, is:

A merchandise guard constructed from a single blank or piece of metal bent to form corresponding right-angularly disposed up-right side members, adapted to fit over and embrace the exposed corners of the lower cases of piled merchandise, a horizontal transverse bottom member extending from the lower end of one side member beyond the outer side edge of the other side member and adapted to fit under the bottom of the corresponding case and a vertical tongue fitting against the inner face and lower end of the last mentioned side member and rigidly secured thereto and inwardly extending hook-like teeth or barbs punched out of the metal forming the side members and the bottom member and tongue of the guard and adapted to engage adjacent faces of the corresponding cases.

In testimony whereof they affix their signatures.

FRANK ARATA.
JOT E. STILES.
